CLAIM

The ornamental design for a food stuff, as shown and
described.

DESCRIPTION

FIG. 1 is a top front and left side perspective view of a
food stuff, showing my new design;

FIG. 2 is a front elevational view thereof;

FIG. 3 is a left side elevational view thereof, the right
side view being a mirror image thereof;

FIG. 4 is a rear elevational view thereof; and

FIG. 5 is a bottom plan view thereof.

FIG. 1.

FIG. 5.

FIG. 2.

FIG. 3.

FIG. 4.
